COKE OVEN BATTERY CONSTRUCTION

William H. Pavitt, Bronxville, N. Y., assignor to
Adele Johnson Wilputte, New Rochelle, N. Y.

Application May 18, 1935, Serial No. 22,241

6 Claims. (Cl. 202—268)

The present invention relates to the construction of a coke oven structure or battery of the so-called underfired type having such ovens and heating walls as are commonly employed in this country and abroad for the manufacture of metallurgical coke, and the general object of the invention is to provide a structure of the type mentioned in which the thermal expansion of individual parts of the structure, occurring as the battery is heated up to its working temperature will not result in the battery elongation heretofore customary.

A coke oven battery of the above mentioned type, comprises horizontally elongated coking chambers alternating with heating walls and, like the latter, extending between the opposite sides of the battery, regenerator chambers and division walls below the level of the coking chambers, and a battery base, or deck member, which underlies and supports all of the above mentioned battery elements and others associated therewith, and which is supported on pillar walls or columns rising from a battery foundation proper. The latter ordinarily rests on, and is supported by the ground which may be reinforced by piles.

The horizontal extent of the base or deck member of a coke oven battery of the type mentioned, and of usual capacity, is considerable. Its width may well be about forty four feet and its length may be two hundred and seventy five feet or so, and the dead load supported by it ordinarily amounts to some twenty five hundred pounds per square foot, so that the base or deck member must possess great strength and rigidity. Heretofore, it has been customary to form said member as a monolith or one piece body or slab or reinforced concrete, about one foot thick.

Modern operating conditions require high battery temperatures. With capacity operation, the bricks at the sides of the oven chambers are heated to temperatures in excess of 2500° F. Those bricks are customarily silica bricks, which enlarge very substantially as they are heated up from atmospheric temperatures to the oven working temperatures. In consequence of their expansion, the horizontal elongation of the lower and major portion of each heating wall is customarily about eight or nine inches. The temperatures and consequent tendency to expansion are lower in the roof structure of the battery and beneath the level of the oven floors. Below that level, the brick temperature diminishes more or less gradually, so that the average base or deck member temperature may be only 250° or so,

though the average temperature of the brickwork directly above said member may be two hundred degrees or so higher.

As the bricks in the battery structure heat up, they expand in the longitudinal direction of the battery, as they do in the transverse direction. In ovens as heretofore constructed, the battery has been prevented from elongating in length in proportion to its increase in width, by the provision of vertically disposed expansion joints in the oven brickwork extending transversely to the length of the battery and provisions for effecting some closing up of those joints as the battery is heated up. Heretofore, however, no attempt has been made to prevent the thermal elongation of the monolithic battery base or deck member on which the coke oven brickwork is supported. On the contrary the effort has been to so regulate or control the thermal expansion of the coke oven brickwork, longitudinally of the battery, that it will be about the same as the deck expansion in the same direction. Such attempts have been attended with indifferent success. Owing to differences between the coke oven brickwork and deck members in respect to the coefficients of expansion of the materials used, particularly with certain deck member concrete mixes, and in respect to the rates of heating and ultimate temperatures attained, the longitudinal expansion of the brickwork and deck cannot be foretold with accuracy, and, in any event, are difficult to control by the only available controlling means. The latter comprises metal tie bars extending longitudinally of the battery at the top of the latter and connecting the upper ends of the pinion or battery end walls, which form abutments engaged by the ends of the coke oven brickwork block. In order that those tie rods may properly regulate the relative expansion of the brickwork and deck they should be slowly lengthened as the battery heating up proceeds through a period of several weeks, so that the tops of pinion walls may slowly spread in accordance with the generally simultaneous elongation of the deck member. In practice, however, it has not been customary to vary the length of the longitudinal tie rods, but to proceed on the assumption that the thermal elongation of those rods as they increase in temperature, will more or less closely correspond to a suitable thermal elongation of the brickwork of the battery.

In accordance with the present invention, I provide the coke oven brickwork with vertically disposed transverse joints, but depart from prior practice by dividing the deck member into a

suitable member of longitudinal sections separated by expansion joint spaces, and by holding the pinions or end walls substantially stationary during the heating up period, so that the expansion joints in the coke oven brickwork and the expansion joints in the deck each take up or close as much or as little as is required to prevent any significant battery elongation. To this end, the pinion walls are preferably anchored firmly at their lower ends to the battery foundation proper which rests on and is imbedded in the earth and does not significantly change in temperature as the coke ovens are heated up, and the upper ends of the pinion walls are connected by longitudinal tie bars which are adjusted during the heating up operation only as required to compensate for the thermal expansion of those bars as their temperatures increase a hundred degrees or so above atmospheric temperatures, as a result of heat absorption from the top of the battery structure on which said bars are mounted.

In its preferred form, the invention is further characterized by the interlocking of sections of the deck member with portions of the oven brickwork above them to prevent relative movement of the parts so interlocked in the longitudinal direction of the battery.

The invention possesses practical advantages particularly in respect to the maintenance of the desired vertical disposition of the coking chambers and heating walls, and in respect to the mechanical connections between the battery structure proper, regenerator waste heat and supply conduits and battery adjuncts such as the benches at the sides of the battery. The latter extend for the full length of the battery and are attached to the battery side armor, but are not subjected to the battery temperatures, and are not subject to significant thermal expansion.

The various features of novelty which characterize my invention are pointed out with particularity in the claims annexed to and forming a part of this specification. For a better understanding of the invention, and the advantages possessed by it reference should be had to the accompanying drawings and descriptive matter in which I have illustrated and described a preferred embodiment of the invention.

50 Of the drawings:

Fig. 1 is a somewhat diagrammatic side elevation of a coke oven battery;

Fig. 2 is a plan view of the deck member supporting the coke oven brickwork of the battery and of the adjacent pinion walls and waste heat flues;

Fig. 3 is a fragmentary section, taken longitudinally of the battery, through the deck member and portion of the oven structure above it; and

Fig. 4 is a partial section, the lefthand portion of which is taken on the line 4—4, and the righthand portion on the broken line 4A—4 of Fig. 3.

The coke oven battery structure illustrated in the drawings comprises a battery foundation A, which ordinarily is a monolithic slab or mat of reinforced concrete, imbedded in, and supported by the earth, and by piles A', when earth conditions require piling, as is usually the case. Anchored to, and extending upward from the foundation mat A are a multiplicity of vertical columns or pillars B, and the two battery end or pinion walls C. Each pinion wall C is a massive body of reinforced concrete, ordinarily formed with recesses C' in its outer or exposed side, al-

ternating with rib or flange portions, whereby suitable transverse wall strength and stiffness is obtained with some economy in the concrete required. The pinion walls C extend approximately to the top of the masonry portion of the coke oven structure, and form abutments for the ends of the coke oven brickwork block D in which the coking chambers, heating flues and regenerator chambers are formed. The said brickwork block D rests upon, and is directly supported by a deck or oven base member E supported on the columns B. The latter, which are much shorter than the end walls C, are spaced apart in rows extending transversely to the length of the battery. In the particular construction illustrated, there are six columns B in each row and a row of such columns directly beneath every alternate coking chamber F. At each end of the battery, the corresponding end of the deck member E is supported on a shoulder C² of the corresponding pinion wall.

In accordance with the present invention, the deck member E is divided into a plurality of longitudinal sections separated by open expansion joint spaces E¹, and the pinion walls C are connected at their upper ends by heavy metal tie rods G, employed, and effective, to prevent the pinion walls from moving away from one another significantly under the thermal expansion stresses occurring as the oven brickwork is heated up to its working temperature. The expansion longitudinally of the battery of the individual sections of the deck member E then occurring, results in a reduction in the thickness of the expansion joint spaces E'. As the oven is heated up, the expansion of the oven brickwork in the direction of the length of the battery is accommodated by vertically disposed expansion joints D' extending transversely of the battery. Those expansion joints may be, and are shown as formed in the manner heretofore customary. Theoretically, however, the joints D¹ in the construction illustrated need to be of a little greater initial width than was required in prior oven constructions, in which the coke oven brickwork block was intended to elongate in the direction of the length of the battery, in accordance with the elongation in the one piece deck member, heretofore employed in such batteries. The lengths of the individual section of the deck member E may vary considerably. In the construction shown, the central sections are somewhat shorter than those nearer the ends of the battery, though this is not essential and the shorter sections are long enough to underlie some eight coking chambers. At their adjacent edges each two sections of the deck member E may be interlocked against relative movement transversely of the battery, as by forming a recess E³ in one of the edges, and by forming a shoulder E⁴ on the other edge which is received in said recess.

In the particular construction illustrated, the eight longitudinal tie rods G employed are suitably spaced apart across the width of the battery and rest on the top of the oven brickwork. To properly distribute the load among the different tie rods G, and to avoid subjecting any one of them to excessive tension, each tie rod G may engage each pinion C through a compression abutment spring H as shown, though ordinarily such springs are not used. As the oven heats up, the temperatures of the long tie rods G are increased sufficiently to produce a significant longitudinal expansion of the tie rods. The effect

of such expansion is taken care of with the construction shown, by dividing each tie rod into sections having their adjacent ends threaded into a connecting turn buckle G¹. As shown, each tie rod includes two turn buckles G¹, one adjacent each pinion wall. Each turn buckle G¹ is rotated to draw together the ends of the corresponding tie rod sections, as required to maintain the desired constant tie rod length, as the rod sections heat up and individually increase in length during the oven heating up operation.

In the preferred construction illustrated, the sections of the deck member E are directly supported by the subjacent columns B through steel girders I of I-beam cross section. Each girder extends transversely of the battery for the full width of the latter, and is supported on the corresponding transverse row of columns B. Preferably, and as shown, a metal bearing plate I' is placed between the top of each girder I and the superposed section of the deck member E. The concrete forming the latter is poured to form the deck member sections in, and the bearing plates I' ordinarily so engage the underside of the deck section above them, that on the expansion of the latter, the bearing plates will not move relatively thereto in the direction of the battery length, but will accommodate such movement of the section relative to the columns B as may occur, by sliding on the girders I.

In the type of oven construction illustrated, the coking chambers F alternate with heating walls J, and each of the latter is supported by a corresponding regenerator division wall K extending transversely of the battery and resting at its lower edge on the subjacent section of the deck member. The heavy load of the coke oven brickwork and associated parts carried by the deck member E, is transmitted to the latter wholly or mainly through the regenerator division walls K. In a preferred form of the present invention, some at least, of the regenerator division walls K are anchored against movement in the longitudinal direction of the battery, relative to the subjacent sections of the deck member E. As shown, this anchorage is effected by forming a shallow groove E⁵ in the upper side of each deck section, to receive each division wall J anchored thereto. In the desirable form of construction illustrated, each section of the deck E is thus anchored only to the two regenerator division walls K adjacent the center of the section and the remaining six or more division walls K supported by the section, are free to slide longitudinally of the battery on said section. In addition to such sliding movements, there are sliding movements of the walls K in the direction of their lengths, as the walls K elongate, due to the thermal expansion, since the walls K have higher temperatures and are made of material having higher coefficient of expansion than the deck E. To facilitate such sliding movements, the sliding surfaces are preferably lubricated initially, as by applying a heavy coating of pitch to the upper sides of the deck sections including the walls of the grooves E⁵ in the initial construction of the coke oven battery.

For the purposes of the present invention, the particular type and form of oven heating flue system employed, is immaterial, subject only to the qualification that the oven is of the under-fired type, and hence comprises rich fuel gas supply channels L vertically disposed in the regenerator division walls K, and communicating at their upper ends with the combustion flues M in the heating walls J, and communicating at their

lower ends with vertical channels L' formed in the deck member E. The fuel gas passing through the channels L and L' is furnished by a gas supply piping system N beneath the deck member E, and including suitable reversing valves, and devices for regulating the flow of fuel gas through the different channels L'. As shown, the lower ends of the channels L are enlarged so that horizontal movement of a wall K relative to the subjacent deck section, will not interfere with the communication between the corresponding channels L and L'. Preferably, and as shown, the channels L' snugly receive, and, in effect, are lined by vertical sections N' of the supply piping N.

Whatever the form or type of oven heating system employed may be, it ordinarily requires a multiplicity of conduit connections O at one or both sides of the battery, between regenerator sole channels P formed in the coke oven brickwork and a waste heat flue Q extending longitudinally of the battery. Relative movement longitudinally of the battery of the ends of such a conduit connection, is obviously objectionable, when significant in amount. Such movement may be substantially avoided in a battery constructed in accordance with the present invention so that there is but little movement of the sole channel P in the direction of the battery length, by forming each waste heat flue Q of suitably short longitudinal sections individually free to expand and connected to another by expansion joints Q'.

While as before stated, the particular form of oven heating system employed is immaterial, it is noted that the desirable construction illustrated herein is of the character disclosed in, and forming the subject matter of my prior application Serial No. 684,131, filed August 8, 1933. In the system illustrated, the vertical heating flues M in half of each heating wall adjacent either side of the battery, are associated with regenerators to form an individual heating unit, which discharges products of combustion into a waste heat flue at the corresponding side of the battery.

The particular coke oven construction illustrated, is a so-called "combination" oven, which may be heated by the combustion of a rich fuel gas supplied to the flues M through the channels L without regenerative preheating, or, alternatively, by the combustion of a lean fuel gas, such as blast furnace gas, which is regeneratively pre-heated. In the combination oven shown, each heating unit comprises an upper horizontal channel M' in the heating wall individual to the unit, and to which all of the flues M of the unit are connected at their upper ends. At their lower ends, an outside group of the flues M of the unit, are connected each by a duct R to an outside regenerator R' at one side of the wall K beneath the flues, and each flue of the group is connected by a duct r to an outside regenerator r' at the opposite side of the wall. Each of the remaining or inside group of flues of the unit is connected by ducts R and r, respectively, to an inside regenerator R² at one side of the adjacent wall K and a second inside regenerator in end to end relation with the regenerator r' and separated from the regenerator R² by the wall K. The outside regenerators R' and r' between each two adjacent walls K, pertain respectively to the different heating units associated with the two heating walls above the walls K, and are separated from one another by a regenerator division wall Rr which is extended to separate the inside re-

generators in end to end relation with the regenerators R' and r' . In the type of oven construction shown, the regenerator division walls R/r are not intended to give any significant support to the coke oven brick work.

Each of the four regenerators of each heating unit has associated with it, a corresponding sole channel P . All of the sole channels P of the unit are connected at the corresponding side of the 10 battery to the adjacent waste heat flue Q by corresponding conduit connections O . Each of the latter includes a reversing valve O' which may be closed to cut off communication between the corresponding sole channel P and waste heat flue Q , 15 and a reversing valve O^2 which may be opened to permit atmospheric air to enter the corresponding sole channel P , when the corresponding reversing valve O' is closed. When the ovens are heated by the combustion of rich fuel gas, all of 20 the regenerators of each unit are used to preheat air. When the oven is heated by the combustion of lean gas, two of the regenerators, for example, the outside regenerator r' and the inside regenerator in end to end relation therewith, are used 25 in preheating the fuel gas. In such use, the reversing valves O^2 in the conduit connections O to the last mentioned regenerators are kept closed, and those regenerators are periodically supplied with lean gas to be preheated therein, by opening 30 reversing valves O^3 provided in extensions OA of the last mentioned conduit connections O . Reversing valves O^3 control the ports in the extensions OA through which lean fuel gas is supplied from a fuel gas supply main S at the side of the 35 battery.

A complete coke oven battery of the type mentioned, comprises numerous battery elements not previously mentioned, including distillation gas take off provisions, oven charging means, coke 40 oven doors, and door frames and other armor, at the sides of the battery, bench structures at the sides of the battery, and charging oven provisions at the top of the battery. While the present invention is not concerned with the form of such 45 additional battery elements, difficulties in respect to the mechanical connections of some of those elements with the coke oven brick work portion of the battery heretofore experienced, are avoided or desirably minimized by the use of the present 50 invention.

In the particular form of coke oven illustrated, the distillation gas take off provisions include an ascension pipe T at each end of each coking chamber mounted on the top of the coke oven 55 brick work, and communicating with a collecting main T' extending longitudinally of the battery and supported on the vertical buckstays U at the corresponding side of the battery. There are one or more buckstays U at each end of each oven 60 heating wall, and subjacent regenerator division wall. Each buckstay is connected at its lower end to the adjacent section of the deck E by an anchor bolt U' and compression spring U^2 , the latter being analogous in function to the previously 65 mentioned compression spring H . At their upper ends, the buckstays U at the opposite sides of the battery are connected by transverse tie bars V extending across the battery at the top of the latter, and each connected at one end, at 70 least, to the corresponding buckstay by a compression spring V' and nut V^2 , the latter being eased off to permit the buckstays to separate as the coke oven brick work expands in the direction transverse to the length of the battery, there 75 being no expansion joints in the coke oven brick

work to accommodate such expansion of the brick work. The fact that the coke oven brick work block D is not permitted to elongate in accordance with the present invention, facilitates the maintenance of the desired vertical disposition of the buckstays which is desirable for various reasons, and particularly because it contributes to the maintenance of the desired vertical disposition of the oven heating walls and door frames.

Benches W at the opposite sides of the battery 10 and having their upper sides located ordinarily a little below the level of the floors of the oven chambers, are practically important adjuncts of a coke oven battery. Such bench structures ordinarily provide enclosures for the reversing 15 valves at the sides of the battery, and supports for the reversing valve operating connections. The tops of the bench structures provide walks 20 for the battery attendants, and the bench at the coke side of the battery, also ordinarily carries the track rails for a coke discharge carriage and for a coke oven door handling machine. The bench structures thus need to be strong and rigid, and ordinarily and advantageously they include a structural metal frame work W' including parts 25 anchored to the buckstays U . The bench structures are maintained approximately at atmospheric temperatures, and displacements of the buckstays U in the longitudinal direction of the battery, occurring as the latter is heated up, involve bench structure disturbances which have been found annoying in the past, and are avoided 30 by the use of the present invention.

As a coke oven battery constructed as described, is heated up to its working temperatures, the 35 thermal expansion occurring in different portions of the battery structure, will be very different as a result of the differences in temperatures obtained and to some extent as a result of the differences in the thermal coefficients of expansion of the materials used in different portions of the structure. In general, the maximum 40 temperatures will be obtained, and the maximum expansion will occur in the portion of the oven brick work between the levels of the tops and bottoms of the coking chambers. The heating wall temperatures at the sides of the coking chambers may be in the neighborhood of, or above 45 250° F. Below the floors of the ovens the brick work temperatures will diminish to an average 50 temperature immediately above the deck E , of something like 400° – 500° F. The deck member E which is continuously exposed to, and cooled by contact with air at its under side, may attain 55 an average temperature of 250° F. or thereabouts. The foundation proper will not be heated significantly above the temperature of the atmosphere. With the deck member formed as a monolith, as has been heretofore customary, it must expand a few inches in the direction of the 60 length of the battery notwithstanding the relatively moderate temperatures to which it is subjected, because of its considerable length. The expansion in the direction of the length of the battery of the deck member, must be accompanied by a similar elongation of the battery brick work 65 above the deck if the various heating walls, buckstays, etc. are to be kept vertical as is desirable. Any significant expansion in the length of the battery structure is objectionable because of its 70 effect on the benches W and other adjuncts of the battery which do not expand similarly. Moreover, it is practically impossible to control the expansion of the brick work above the deck 75 so that it will be exactly the same as the deck ex- 75

pansion, particularly as the temperatures in the different portions of the structure, do not change proportionally as the temperatures are being increased throughout the heating operation. With the use of the present invention, however, it is practically feasible to hold the deck and the brick work above it against significant elongation in the direction of the length of the battery and thus maintain the desired vertical disposition of the heating walls and buckstays as well as avoiding the other objections to battery elongation.

While in accordance with the provisions of the statutes, I have illustrated and described the best form of embodiment of my invention now known to me, it will be apparent to those skilled in the art that changes may be made in the form of the apparatus disclosed without departing from the spirit of my invention as set forth in the appended claims and that in some cases certain features of my invention may be used to advantage without a corresponding use of other features.

Having now described my invention, what I claim as new and desire to secure by Letters Patent, is:

1. A regenerative under fired coke oven battery structure comprising in combination an elongated brickwork block formed with horizontal coking chambers arranged side by side and each extending transversely to the length of the block between the sides of the battery and with heating walls alternating with the coking chambers and with walls beneath and parallel to the heating walls directly supporting the latter and separated from one another to provide regenerator spaces, said block being formed in sections arranged end to end longitudinally of the battery and separated by expansion joints extending transversely to the length of the battery, of supporting means for said block comprising battery end walls anchored against substantial relative movement and having their upper portions in abutting relation with the respective ends of the brickwork block, a deck member beneath and directly supporting the weight of the block and formed of sections arranged end to end longitudinally of the battery and each extending transversely of the battery from one side to the other thereof and separated from each adjacent section by an expansion joint extending transversely to the length of the battery, and each directly supporting a portion of said block including a plurality of said chambers, heating walls and spaces, vertically-disposed, spaced-apart supports for said deck member sections, and a foundation supporting said supports and separated by the latter from said deck member to provide a space between the latter and the foundation forming the passageway for an oven attendant required for under-fire operation, and making the foundation temperature substantially lower than the temperature of the under-side of said deck member.

2. A coke oven battery structure as specified in claim 1, in which adjacent deck member sections have their adjacent edges configured to interlock said sections against relative horizontal movement transversely of the battery length.

3. A coke oven structure as specified in claim 1, in which each section and the portion of the brickwork block directly supported thereby, have shoulder portions interlocking them against relative bodily movement in the longitudinal direction of the battery.

4. In the construction of an under-fired regenerative coke oven battery comprising a coke

oven brickwork block formed with side by side horizontal coking chambers and with heating walls at the sides of the coking chambers and with subjacent supporting and regenerator separating walls all extending between the opposite sides of the battery, and with expansion joints extending between the opposite sides of the battery and distributed along the length of the latter, a deck member underlying and supporting said block and forming the roof of a space forming the passageway for an oven attendant required for underfire operation, and battery end walls between which said block and deck extend, the method which consists in holding said end walls against substantial movement away from one another and taking up in the deck member the thermal expansion thereof in the longitudinal direction of the battery, while the battery is being heated up to its working temperatures, and thereby preventing battery elongation during the heating up operation.

5. A regenerative under-fired coke oven battery structure comprising battery end walls, a deck member extending between said end walls and formed in sections arranged end to end longitudinally of the battery and separated by transverse expansion joints, a coke oven brickwork block mounted on said deck and extending between said end walls and formed with horizontal coking chambers arranged side by side and each extending between the opposite sides of the battery and with heating walls alternating with the coking chambers and with walls beneath, parallel to, and supporting the heating walls and oven chambers, and separated from one another to provide regenerator spaces, said block being formed in sections arranged end to end longitudinally of the battery and separated by transverse expansion joints, and means for supporting said deck member and end walls and holding the latter against substantial movement away from one another, whereby the thermal expansion of said sections is taken up by said expansion joints without appreciable elongation of the battery, said means comprising parts distributed along the length of the battery beneath and supporting said deck, and a foundation supporting said end walls and parts and separated by the latter from said deck member to provide a space between the latter and the foundation forming the passageway for an oven attendant required for underfire operation and making the foundation temperature substantially lower than the temperature of the under-side of said deck member.

6. A regenerative under-fired coke oven battery structure comprising battery end walls, a deck member extending between said end walls and formed in sections arranged end to end longitudinally of the battery and separated by transverse expansion joints, a coke oven brickwork block mounted on said deck and extending between said end walls and formed with horizontal coking chambers arranged side by side and each extending between the opposite sides of the battery and with heating walls alternating with the coking chambers and with walls beneath, parallel to, and supporting, the heating walls and oven chambers, and separated from one another to provide regenerator spaces, said block being formed in sections arranged end to end longitudinally of the battery and separated by transverse expansion joints, and means for supporting said deck member and end walls and holding the latter against substantial movement away from one another, whereby the thermal expansion of said

sections is taken up by the expansion joints without appreciable elongation of the battery, said means comprising tie rods connecting the tops of said end walls, parts distributed along the length of the battery beneath and supporting said deck, and a foundation supporting said end walls and parts and spaced by the latter from said deck

member to provide a space between the later and the foundation forming the passageway for an oven attendant required for under-fire operation and making the foundation temperature substantially lower than the temperature of the 5 under-side of said deck member.

WILLIAM H. PAVITT.
